EDMUND CLIFTON CARVER, OF BURGESS HILL, ENGLAND

STRAINING DEVICE FOR LAWN TENNIS NETS

Application filed December 11, 1928, Serial No. 325,235, and in Great Britain December 13, 1927.

This invention relates to straining devices for nets used in the game of lawn tennis and the like, and has for its object to provide an improved and simplified construction thereof.

To this end, a straining device constructed in accordance with this invention comprises a wheel rotatably mounted on a horizontal axis in a support and adapted to engage either a chain which is connected to one end of a wire or rope passing through the top of the net or the said wire or rope, said wheel being prevented from rotating in the direction of the pull of the wire by means of one or more roller members, wedges or cams 15 engaging with the said wheel and the said support.

Referring to the accompanying drawings, Figure 1 is a side elevation of one form of straining device constructed in accordance with this invention; Figure 2 is a sectional side elevation; and Figure 3 is a plan view.

a is a sprocket wheel engaging a chain *b*, said wheel *a* rotating on a spindle *c* which 25 is rigidly fixed in each side of the bifurcated head *d* which may be formed in one with or attached to the post *e*.

The sprocket wheel *a* has one face countersunk as at *f* and is formed with a plurality of teeth *g*. The said teeth *g* are adapted to be engaged by means of the tooth or projection *h* formed on the lever *j*. The said lever *j* is formed with an elongated slot *k* and is mounted on the spindle *c*. *l* is a 30 curved bracket secured to the bifurcated head *d* and disposed between said bracket *l* and the periphery of the wheel *a* are two rollers *m*, *m*—one being smaller than the other. Slidably mounted in bracket *l* is a member *n*.

In use, the chain *b*, which may be attached to a wire or rope passing through the top of the net, is passed over the sprocket wheel *a*. The lever *j* is then first raised in order that 45 the tooth *h* may engage one of the teeth *g*

and then moved downwardly in an arc, that is, in a clockwise direction.

Any movement of the wheel *a* in a counter clockwise direction forces the rollers down between the bracket *l* and periphery of the wheel *a*, causing a wedging action, and rotation is prevented. When it is desired to release the wheel *a*, the member *n* is slid upwardly in order to force upwards the rollers *m* and as soon as the said rollers are 50 disengaged from the said bracket and periphery, the wheel is free to rotate.

Manifestly, the construction shown and described is capable of many modifications and such modifications as come within the 55 scope of my claim, I consider within the spirit of my invention.

What I claim is:—

In a device of the character described, a 60 rotatably supported wheel, a bracket having an internally curved surface fixed adjacent said wheel and partially surrounding the peripheral portion thereof, a plurality of frictional rollers freely received between the peripheral portion of the wheel and the internally curved surface of the bracket, said rollers being adapted with movement of the wheel in one direction to be forced between the peripheral portion of said wheel and the adjacent internally curved surface of the bracket, causing a wedging action and preventing rotation of the wheel in that 65 one direction, the rollers being of different diameters whereby to prevent them from 70 mutual interference during their wedging action and means slidably in said bracket and adapted to be brought into contact with the smaller of said rollers and force the same against the adjacent larger roller for disengaging said rollers from the wheel and 75 bracket.

In testimony whereof he affixes his signature.

EDMUND C. CARVER. 80
